Chamberlain & Newman ATTORNEYS.

UNITED STATES PATENT OFFICE.

GEORGE W. GARDNER, OF BRIDGEPORT, CONNECTICUT.

CORSET-CLASP.

1,390,776.

Specification of Letters Patent. Patented Sept. 13, 1921.

Application filed March 1, 1921. Serial No. 448,781.

To all whom it may concern:

Be it known that GEORGE W. GARDNER, a citizen of the United States, and resident of Bridgeport, in the county of Fairfield and State of Connecticut, has invented certain new and useful Improvements in Corset-Clasps, of which the following is a specification.

This invention relates to new and useful improvements in clasps such as are used in connection with a stud for securing two portions of a garment together, as for instance, corsets and when it is designated as a corset clasp, or again when employed for supporting one garment from another, as when connecting a brassière to a corset for holding the former in position.

The object of the invention is to provide a metal clasp for the above purpose which will not become unfastened when once connected to a stud, but which may be readily disconnected by the user when desired, and particularly to provide a loop form of clasp, that may consist of a single piece of sheet metal and adapted to be directly attached to a length of tape, webbing or other material, so as to be readily connected with a button or stud mounted upon the adjoining member; further to provide a particular shaped opening in the loop through which the head of the stud is inserted and including a reduced socket portion in which the shank of the head may be normally seated, and also to provide a yieldable tongue, whose free end is disposed in alignment with the reduced socket so as to engage the head of the button when the clasp is attached or detached from the stud and to prevent the stud from becoming detached.

With these and other objects in view the invention resides and consists in the construction and novel combination and arrangement of parts hereinafter more fully described, illustrated in the accompanying drawings, and pointed out in the claim here-to appended, it being understood that various changes in the form, proportion, size and minor details of construction within the scope of the claim may be resorted to without departure from the spirit or sacrificing any of the advantages of the invention.

Similar characters of reference denote like or corresponding parts throughout the several figures of the accompanying drawings forming a part of this specification, and upon which,

Figure 1 shows a front elevation of a corset employing a series of clasps constructed in accordance with my invention, and also illustrates a brassière having a depending tape upon the lower end of which is secured one of my improved clasps and shown detachably connected to one of the studs of the corset.

Fig. 2 shows an enlarged detached front view of the tape and clasp shown in Fig. 1 secured to the brassière and connected to the corset stud.

Fig. 3 shows on an enlarged scale, one of the corset clasps employed in Fig. 1.

Fig. 4 shows a central vertical section and front elevation respectively upon an enlarged scale, of the clasp shown in Fig. 2, and

Fig. 5 shows a cross sectional view through a corset stay with stud attached and my improved clasp in the act of being disconnected from the stud.

Referring in detail to the characters of reference marked upon the drawing, A represents a corset and B a brassière. 7 represents one of the front corset stays carrying a series of studs 8 for engagement by the clasps 9. 10 designates the other of the pair of front corset stays to which a series of my improved clasps 9 are fastened in alignment with and for connection to the studs upon the first mentioned corset stay. It will be obvious of course that the purpose of the stay and studs upon the one side and the stay and clasps upon the other is to detachably connect the two adjacent front edge portions of the corset together and to properly secure the same upon the wearer. The studs herein designated as 8 may be of the usual commercial type of stud having a head a, shank b, shoulder c and rivet end portion d for attachment to the stay in the manner shown in Fig. 5, or may be of any other headed form of stud so far as the application of my invention may require.

The novel clasp of the invention is made of a single piece of metal by one or more stamping operations as may be required and in this connection it can be varied slightly to better adapt it to the particular style of tape, stay or garment to which it is to be attached, as for instance in Fig. 3 where the clasp is shown attached to a corset stay by means of a pair of rivets 11, the clasp would necessarily be provided with two holes to align with holes in the stay and through

which the rivets are inserted and headed for securing the clasp thereto. In Figs. 2, 4 and 5 the fastening end of the clasp is provided with slots 12 and 13, and a toothed edge 14 through which a tape 15 may be threaded for securing the clasp to the tape for use on brassières as shown.

The more important features of the clasp are situated in its lower reduced end portion and comprise a relatively large opening 16 which is of a diameter slightly greater than that of the head of the stud, a relatively smaller pocket portion 17 formed in the lower end portion of the clasp to receive the shank of the stud, and a tongue 19, the free end of which is disposed central of the clasp and into the opening to engage the shank and head of the stud. Said tongue being formed by cutting inwardly disposed diverging slots 18 as shown.

It will be understood from Fig. 5 that the pocket 17 heretofore featured, to receive the shank of the stud, not only serves to better seat the stud when the two parts are connected, but also serves to accommodate the shank when the clasp and stud are to be disconnected. In this operation the parts are first positioned at an angle to each other, whereby the stud is crowded into the pocket which allows the head of the stud to pass through the wider opening 16 against the slight resistance of the end of the tongue 19

as shown in Fig. 5. This form of positioning of the two parts is practically the same in the attachment of the clasp to the stud as in the removal of the clasp from the stud, except that in the one instance the end of the tongue follows in over the top of the head while in the other instance it follows out under the head.

Having thus described my invention, what I claim and desire to secure by Letters Patent, is:

A sheet metal clasp having means for attachment to a garment and an opening of general circular configuration to receive the head of a stud, said opening having in its side farthest from said means for attachment a relatively small pocket of general semi-circular configuration, and a tongue tapered both as to thickness and width, extending into the circle of said opening for a distance about equal to the depth of said pocket, said tapered tongue being in the plane of said clasp and being defined by diverging slots cut in said metal.

Signed at Bridgeport, in the county of Fairfield and State of Connecticut this 26th day of February A. D. 1921.

GEORGE W. GARDNER.
